UNITED STATES PATENT OFFICE.

PETER W. MOSHER, OF STOCKTON, CALIFORNIA.

TRAIN-CONTROL SYSTEM.

Application filed April 29, 1925. Serial No. 26,689.

This invention relates to improvements in railway equipment, and especially to automatic electric setting systems of the normally closed circuit type, in which the opening of the circuit causes the brakes to be applied, such opening occurring under certain operating conditions, as hereinafter seen.

The system of my present invention is incorporated in connection with the ordinary block signal system and is installable on each track of a double track road, or it may be also employed on single track railways.

The principal object of my invention is to provide normally closed circuits on the different engines, arrange a track circuit which controls the opening of the engine circuit itself, and interpose connections between the semaphores of the block signal system and said track circuit in such a manner that the brakes on an engine entering the block in which the semaphore is set against the engine will be automatically set regardless of any train ahead.

At the same time the brakes are not applied on a head train going in the same direction as a following train as on a double track road, permitting the head train if still in the block to continue on its way so that it may get out of said block as soon as possible.

Another object is to arrange the system in such a manner that in the event that the head train fails to set the semaphore the presence of such train in the block will cause a brake application to be made on any train entering the block past the inoperative semaphore.

Therefore with my improved system, while the automatically actuated block signal semaphores, as at present used, will cause an automatic stopping of a train to be effected, if the train passes a semaphore set against it, at the same time the failure of the semaphore to function will not affect the operation of my system if another train is in the block ahead of the semaphore. Of course if the semaphore is down and there is no train in the block ahead the brakes on a train then entering the block will naturally not be set, since the track is clear.

These objects I accomplish by means of such structure and relative arrangement of parts as will fully appear by a perusal of the following specification and claims.

The figure on the drawing is a diagrammatic plan of my improved system shown on a one-way track with two adjacent semaphores of a block system and indicating two trains, one between the semaphores and the other just entering the block; the rear semaphore having been set by the head train.

Referring now more particularly to the characters of reference on the drawings, the numerals 1 and 2 denote the rails of each track insulated from each other but continuous between adjacent semaphores S and S', at which points they are also insulated from the corresponding rails therebeyond at both ends.

Adjacent the semaphores are third rail lengths 3 insulating from the main rails and from each other. At each semaphore is located a pair of spaced leads 4 and 5. The lead 4 is connected to the rail 1 on one side of the insulation break while lead 5 connects to the rail 1 on the other side of said break. The lead 5 also has a lead 6 connected thereto and extending to the third rail 3 with a battery 7 interposed therein. This battery may be that used to operate the semaphore if desired, or it may be an individual unit.

Each semaphore arm 8 is connected to a switch or contact member 9 arranged when the semaphore is set or raised to a horizontal position to bridge across the leads 4 and 5. When the semaphore arm is down or in the clear position said member 9 is spaced from said leads as shown.

Leads 10 extend from the rail sections 2 centrally of their length between the semaphores to a common continuous lead 11 formed as a wire supported from the usual pole line found alongside the tracks.

The foregoing forms the standing or track circuit arrangement usable in connection with the engine circuits now to be described.

In such description I only show the main features of such circuits since the additional features, such as visible or audible signals, hand operated switches and the like do not affect the operation of the system itself.

In the figure I have indicated two engines A and B travelling in the same direction or from left to right on the drawing.

Each engine has lead wheels 13 and a shoe or contact 14 adapted to engage the third rail 3 and insulated from the wheels and the remainder of the engine. A lead 15 is connected to one wheel and leads to one terminal.

of a magnet 16, the other terminal of the engine 10 magnet being connected to a lead 17 which runs back to the wheels. Interposed in the lead 15 is a battery 18 and an overload circuit breaker 19 between the battery and the magnet. The circuit through the wheels and leads 15 to 17 and the parts therebetween is therefore normally closed regardless of the third rail or shoe causing the magnet 16 to be normally energized. It is to be noted that while the current normally passes through the circuit breaker it does not trip or throw the same, since the strength of the single battery 18 is insufficient to 15 overload the circuit breaker to the extent necessary to cause it to throw.

The armature 20 of the magnet is therefore normally held thereagainst, said armature being suitably connected to the operating lever or handle 21 of the air brake valve 22, which under the above conditions is closed. A spring 23 of insufficient strength to overcome the pull of the magnet tends to move the armature away from the same. If 25 the circuit is broken from any cause intentionally or otherwise, the magnet will be de-energized and the spring will then act to move the armature and set the brakes.

Between the magnet 16 and circuit breaker 30 19, a lead 24 is connected to the lead 15, which lead 24 extends to one terminal of a magnet 25 disposed in opposed relation to the magnet 16 and adapted to also act on the armature 20. The lead 26 from the other 35 terminal of the magnet 25 is connected to the shoe 14. This forms a shunt, avoiding the magnet 16 while retaining the battery 18 in the circuit. The magnet 25 may be omitted if desired but its use enables quicker action 40 on the armature to be had than if the spring 23 alone were depended on.

In the figure it is assumed that the engine 45 A has set the semaphore S when passing by the same. This is done by the front wheel of the engine passing over the adjacent main rail break and causing the usual semaphore actuating circuit to be broken, an operation which raises the semaphore and with my improved system causes a connection to be 50 made between the leads 4 and 5. Since block signal systems are now commonly used on practically all railroads, and the means used to operate the semaphore arms are well known to those skilled in the art, it appears 55 unnecessary to show or describe such means, especially since the particular semaphore raising mechanism forms no part of my invention.

In order to insure that the brakes will not 60 then be applied to the engine setting the semaphore the length of the rail 3 beyond the insulation break in the direction of movement of the engine, is shorter than the distance from the front wheels 13 to the shoe 65 14, which is at the extreme front end of the

main rail break to set the semaphore.

In operation with the engines in position as shown in the figure, the engine A is not 70 affected by the engine B and is free to continue on its way. The engine B, however, entering the block at the semaphore S, which is set, will instantly have a brake application made thereon.

75 This is because a circuit is closed in which both batteries 7 and 18 are included, causing the circuit breaker 19 to throw and break the circuit through the magnet 16 thereby releasing the arm 20. At the same time the magnet 25 will be energized acting in conjunction with the spring 23 to move the armature and make forcible application of the brakes.

85 This circuit may be traced from the battery 7, along the lead 6 to and across the member 9, along the lead 4 to the rail 1, through the wheels 13 to the lead 15, through the battery 18 to the circuit breaker, along the lead 24, through the magnet 25 to and 90 along the lead 26 to the shoe 14, rail 3, and back to the battery 7 through lead 6. This will cause the magnet 25 to be energized as above stated. At the same time the double strength of the two batteries, passing 95 through the circuit breaker, causes the same to throw and deenergize the magnet 16. The current from the battery 7 passes along the lead 15 to the battery 18 to add its strength thereto, rather than passing along the lead 17 toward the magnet 16 to buck said battery 18, because the former passage offers less resistance to the flow of the current than the passage in which the magnet is interposed. As soon as the shoe 14 clears the rail 100 3 this latter circuit will be broken and the original circuit again closed provided of course the engineer sets the circuit breaker by hand, as is necessary. The brakes will not 105 then be released, however, as the distance to 110 which the armature has moved is too great for the magnet 16 to then exert any positive influence on said armature. The brakes can only be released by turning the handle 21 to the off position by hand, when the armature 115 will be moved to within the sphere of influence of the magnet 16 and will be then engaged and held by the latter ready for another operation.

120 From the foregoing description it will be readily seen that I have produced such a device as substantially fulfills the objects of the invention as set forth herein.

125 While this specification sets forth in detail the present and preferred construction of the device, still in practice such deviations from such detail may be resorted to as do not form a departure from the spirit of the invention, as defined by the appended claims.

130 Having thus described my invention what

I claim as new and useful and desire to secure by Letters Patent is:

1. An automatic brake setting system for railway vehicles including with a normally closed electric brake holding circuit on each vehicle, said circuit including a source of current and an overload circuit breaker therein; a track circuit having an independent source of current therein, means incorporated with said track circuit whereby if two vehicles are within a certain distance of each other and travelling in the same direction the strength of the sources of current of the track side circuit and that of the rear vehicle will be united to cause the circuit breaker on the rear vehicle to throw, and means whereby such operation will cause a brake application to be made on such rear vehicle without affecting the vehicle ahead. 20 25 30 35
- 10 having a source of current therein, means whereby if the arm is moved and a vehicle passes the same the strength of the two sources of current will be united in a common circuit to cause the overload circuit breaker to throw, and means whereby such operation will automatically cause an application of the brakes on the vehicle to be made.
- 15 2. An automatic brake setting system for

railway vehicles including with a normally closed electric brake holding circuit on each vehicle, said circuit including a source of current and an overload circuit breaker therein; a track circuit having an independent source of current therein, means incorporated with said track circuit whereby if two vehicles are within a certain distance of each other and travelling in the same direction the strength of the sources of current of the track side circuit and that of the rear vehicle will be united to cause the circuit breaker on the rear vehicle to throw, and means whereby such operation will cause a brake application to be made on such rear vehicle without affecting the vehicle ahead. 20 25 30 35

In testimony whereof I affix my signature.

PETER W. MOSHER.
